UNITED STATES PATENT OFFICE.

WILLIAM HARDER, OF REMSEN, IOWA.

AUTOMATIC CROSSING GATE.

Application filed June 16, 1924. Serial No. 720,237.

To all whom it may concern:

Be it known that I, WILLIAM HARDER, a citizen of the United States, and a resident of Remsen, in the county of Plymouth and State of Iowa, have invented certain new and useful Improvements in Automatic Crossing Gates, of which the following is a specification.

My invention relates to crossing gates for railway crossings, particularly of the type that are automatically actuated by the passing of a train, and it is my object to provide such a gate construction which is of simple, durable and inexpensive construction.

More particularly it is my object to provide a gate pivoted for movement in a vertical plane, a motor operatively connected with the gate and adapted to move it from open to closed position, and vice versa, and controlling means for starting and stopping the motor, including an electric circuit, which electric circuit includes a section of the rails of the track and is thus completed when a train contacts with the section or "comes into the block".

Another object is to provide a balanced gate and a relatively small spring-driven motor, the gate being such that continued rotation of the motor in the same direction during successive periods of operation will respectively lower and raise the gate. By using the balanced gate, very little power is required from the motor, and a spring motor may thus be utilized which is adapted, from the winding, to store enough energy to actuate the gate during the period of twenty-four or forty-eight hours.

More specifically it is my object to provide in the controlling mechanism for the motor means for starting the motor when the train enters and leaves the block, respectively, and automatic means forming part of the motor for checking the rotation thereof at the end of a predetermined period of such rotation.

Utilizing the structure generally set forth in the preceding objects, it is my purpose to provide an automatic crossing gate actuated by a spring motor of such construction that it will not readily get out of order, and controlled by an electric controlling system, utilizing the block system which has proven very satisfactory in controlling railway signals.

Another object is to provide a resilient

connection between the motor and the gate whereby the sudden checking of the gate by an obstruction interposed between its path of movement will not suddenly check the operation of the motor so as to injure the same. Such spring connection is designed also to serve the purpose of such resilient connection, allowing the motor to start while the inertia of the gate continues to hold it back, and then to accelerate the movement of the gate after it has started.

A further object is to provide a signal light carried by the gate and controlled by movement of the gate to closed position.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a perspective view of my improved crossing gate, the grease casing at the ends of the lever arm being omitted.

Fig. 2 is an elevation of a portion of the motor showing the driven shaft and the crank arm thereon, together with a portion of the lever arm and connecting link.

Fig. 3 is a detail sectional view through the light switch.

Fig. 4 is a plan view of the motor, the house therefor being shown in section.

Fig. 5 is a vertical sectional view through the housing, showing the motor and source of electrical energy in elevation.

Fig. 6 is a diagrammatic view of the entire apparatus.

Fig. 7 is a detail view illustrating the mounting of the gate, parts thereof being shown in section.

Fig. 8 is a detail sectional view through the end of the lever arm and the resilient connection between the arm and the gate, and

Fig. 9 is an enlarged detail sectional view through the governor shaft of the motor, illustrating one of the brake arms.

In Fig. 1 I have shown at 10 the rails of the ordinary railway track, and at 11 a highway crossing the track. The gate is supported by the posts, 12, which are suitably mounted by the side of the rails, 10, and adjacent the highway, 11, so that the gate, when in lowered position, will extend

entirely across the road. The gate I have shown merely for the purpose of illustration as a long beam, 13, in which is mounted near one end thereof the roller bearing, 14, on which the gate is pivoted. The gate is mounted between the posts, 12, by means of the bolt or shaft, 15, which extends through the posts and through the bearing, 14. The roller bearing, 14, may be of the ordinary construction, as used for the axles of automotive vehicles.

It will be seen that the gate is thus mounted so as to rotate very freely on its axis. I provide a counter-weight for the lower end of the gate, which may be of any suitable construction, but the one I have shown comprises the bars, 16, fixed to the lower end of the beam, 13, and on which is slidably mounted the weight, 17. A set screw, 18, allows adjustment of the weight, 17, relative to the axis of the gate in order to balance the gate.

I provide a spring motor for actuating the gate which is preferably mounted in a housing, 19, situated near the track and which is closed by a door, 20, and locked by a suitable locking means, 21. The motor is thus protected from the weather and from intruders.

The motor is mounted on a shelf, 22, within the house, 19, and comprises a base, 23, to which is fixed the side upright frame members, 24. The power is derived from a spring, 25, mounted on a shaft, 26, and is transmitted to the driven shaft, 27, through the medium of the large gear, 28, and the pinion, 29. The gear, 28, is loosely mounted on the shaft, 26, and is connected with the spring, 25, through the medium of the ratchet, 30, and pawl, 31.

The structure just described is of the ordinary construction usually found in clocks and other devices using spring driven motors.

In order to wind the spring I provide the pinion, 32, in mesh with the winding gear, 33. The pinion, 32, is mounted on a stub shaft, 34, fixed to the frame, 24, and has the pins, 35. A crank, 36, is provided having the socket, 37, and the slots, 38, therein to receive the pins, 35. The socket, 37, is adapted to fit over the end of the shaft, 34. In winding the gear is turned, as indicated by the arrow, 39. The gear, 33, may be made larger than the gear, 32, in order to increase the leverage exerted upon the spring by the winding crank. The driven shaft, 27, extends through the back of the house, 19, and on its end is mounted the crank arm, 40.

In order to transmit the power from the motor to the gate I provide the following means. Pivoted to a suitable post, 41, mounted between the house, 19, and the gate is a lever arm, 42, which extends behind and

approximately to the center of the house in one direction and adjacent the gate in the other direction. Connecting the crank arm, 40, with the arm, 42, is a link, 43, which is pivoted to the lever by means of a suitable pin or bolt, 44. A housing, 45, encloses the end of the lever arm and may be filled with grease through the grease cup, 46. A roller bearing may be used to form a connection between the pin, 44, and the lever 42.

Pivoted between the bars, 16 at 47, is the upwardly-extending rod, 48. Pivoted by means of the pin or bolt, 49, to the end of the lever arm, 42, are the downwardly-extending rods, 50. A roller bearing connection, 51, may be provided between the pin, 49, and the arm, 42. Fixed to the rods, 50, intermediate of their length is a cross plate, 52, having at its center an opening, 53, through which the upper end of the rod, 48, is slidably mounted. Fixed to the rod, 48, near the lower ends of the rods, 50, is a bar, 54, having the openings, 55, at its ends, through which are slidably received the lower ends of the rods, 50. A spring, 56, encircles the rod, 48, between the plate, 52, and the bar, 54, and is connected thereto as shown. It will be seen that a resilient connection is thus provided between the end of the lever, 42, and the rod, 48, whereby movement of the rod either toward or away from the lever will be resisted by the spring, 56.

It will be seen from the foregoing description that as the arm, 40, rotates from the position shown in Fig. 2 to a position where it extends vertically downward that the lever arm, 42, will be drawn to the position shown in dotted lines in Fig. 1, and the gate lowered to the position shown in dotted lines in Fig. 1. When the arm, 40, rotates through another 180°, the gate will be raised again to the position shown in full lines. It will thus be seen that in order to properly control the movement of the gate it is necessary to control the rotation of the shaft, 27, through successive periods of 180° respectively.

I will now describe the means for controlling the motor. Mounted on the frame, 24, is the governor shaft, 57, having the pinion, 58, which is connected through a train of gears, 59, to the shaft, 27, so that rotation of the shaft, 27, will cause the shaft, 57, to revolve very rapidly in the direction indicated by the arrow, 60. The ordinary fan governor, 61, is provided for controlling the speed of the shaft, 57, while rotating.

On the governor shaft, 57, is a brake arm, 62, which is normally held against rotation by the upwardly-extending lip, 63, on the armature, 64, which is welded or otherwise suitably secured to the lower end of a pawl, 65. The pawl, 65, has the laterally-extending arms, 66, on the ends of which are the

up-turned ears, 67, through which is extended the rod, 68, serving to pivot the pawl, 65, and the armature, 64, for swinging movement. In order to release the 5 brake arm, 62, I provide the electro-magnets, 69, which are positioned under the end of the armature, 64, so that when energized, the lip, 63, will be drawn downwardly out of the path of movement of the brake arm, 10 62.

For energizing the magnets, 69, I provide the cells, 70, which are preferably storage batteries. It may be mentioned here that 15 part of the circuit through which the current for energizing the magnets, 69, flows, includes the rails, 10.

Referring, now, to the diagram shown in Fig. 6, the rails, 10, adjacent the highway are shown insulated from the remainder of 20 the track, as at 71. One side of the electro-magnet, 69, is connected to the storage battery, 70, through the wire, 72. From the other side of the magnet, 69, the wire, 75, leads to one of the rails, 10. From the 25 other rail, 10, the wire, 76, connects back to the battery, 70.

It will thus be seen that when the wheels, 77, of a train contact with the insulated portions of the rails a circuit will be established 30 through the rails, 10, the wheels and axles, 77, the wire, 75, the magnet, 69, the wires, 72, the battery, 70 and the wire 76, back to the other rail, 10. When the circuit is thus established the armature, 64, will be 35 drawn downwardly so as to release the brake arm, 62, and to allow the motor to rotate until the shaft, 27, has made half a revolution. When this has been done, the motor is stopped by the means which I will now describe. 40

I provide a second armature, 78, fixed to a stop arm, 79, which in turn is pivoted to the frame in a manner similar to the pawl, 65. On the end of the armature, 78, is the 45 upwardly-extending hook, 80, normally positioned just below the end of a brake arm, 81, similar to the brake arm, 62. A rod, 82, limits the motion of the stop arm, 79, and thus properly positions the end of 50 the armature, 78, under the brake arm, 81. A weight, 83, adjustably mounted on the armature, 78, by means of a screw, 84, received through a slot, 85, in the armature, tends to urge the end of the armature 55 downwardly away from the brake arm, 81.

To stop the motor when the arm, 40, has made a half revolution I provide the magnet, 86, mounted under the other end of the armature and adapted when energized to move the hook, 80, upwardly in the path of movement of the brake arm, 81. I provide 60 automatic means for controlling the magnet, 86, including a switch mounted on the shaft, 27, for rotation therewith. This 65 switch may comprise a flexible arm of brass,

or the like, 87, adjustably secured to the shaft, 27, by means of the looped portion, 88, and the bolt, 89. A brush, 90, is mounted on an insulating block, 91, fixed to the frame, 24, and is connected by means of a 70 wire, 92, to the battery, 70. One side of the magnet is grounded to the frame so as to make electrical connection with the rotating arm, 87, and the other side is connected through the medium of the wire, 74, 75 the knife switch, 73, and the wire, 75, to one of the rails, 10.

It will now be seen that when the shaft 27, has rotated 180° from the position shown in Fig. 5, the arm, 87, will contact with the 80 brush, 90, as illustrated in dotted lines in Fig. 5, and a circuit will be established through the brush, 90, the wire, 92, the battery, 70, the wire, 76, the rails, 10, the wire, 75, the switch, 73, the wire, 74, the magnet, 85 86 and the frame, 24. The armature, 78, will then be drawn downwardly and the hook, 80, will be moved into the path of the brake arm, 81. In this connection it will be noted that the brake arm, 81, is mounted 90 on the shaft, 57, so as to engage it frictionally and yet to rotate thereon when suddenly stopped by the hook, 80.

In order to so mount the arm, 81, it is provided with the collar, 93, which encircles 95 the shaft, 57, and is split and provided with the ears, 94, which receive the adjusting screw, 95. Thus the tension may be adjusted so that the inertia of the moving parts of the motor may be expended in rotating the shaft, 57, against the friction of the ring, 93, after the brake arm, 81, has been arrested. The brake upon the shaft is such that it will quickly be brought to a 100 stop for stopping the motor. The brake 105 arm, 62, is similar in construction to the brake arm, 81.

In order to raise the gate the motor must again be set in motion. To do this the 110 brake arm, 81, is released by the hook, 80. This in turn is accomplished by breaking the circuit through the magnets, 86, and it will be seen that when the train leaves the block the circuit will be so broken and the motor will be allowed to operate, rotating 115 the arm, 40, from its position extending downwardly toward its upper position.

It may be mentioned here that at many times the train may be delayed while in the block and it may be desirable to raise the 120 gates while the train remains there. For this purpose the switch, 72, is provided, and it will be seen that the opening of the circuit by releasing the switch, 73, will cause the motor to operate for raising the gate. There 125 would be no necessity of again lowering the gate while the train remained in such position or before it proceeded on its journey, and therefore I have not provided means for so doing. 130

When the gate has been raised to its open position the motor is again stopped by the lip, 63, on the armature, 64. The armature, 64, is provided with a weight, 96, similar to 5 the weight, 83, which tends to move the lip, 63, into the path of the brake arm, 62.

It will be seen that during the time that the gate is being lowered and the motor being controlled by the armature, 78, the 10 armature, 64, must be rendered inoperative in order that the rotation of the shaft, 57, will not be prevented by the lip, 63. For this purpose I provide the disk, 97, mounted 15 on the shaft, 27, and so positioned in the path of swinging movement of the pawl, 65, as to maintain the armature, 64, in the position to which it has been urged by the magnet, 69, while the shaft, 27, is making a 20 complete revolution. Thus it will be seen that after the circuit through the magnet, 69, has been broken by the departure of the train from the block, the lip, 63, will be maintained out of engagement with the 25 brake arm, 62, in order to stop the motor a notch, 98, is provided in the disk, 97, which is so positioned relative to the other parts of the motor that when the shaft, 40, has assumed its upper position the pawl, 65, will drop into the notch and allow the parts 30 to assume the position shown in Fig. 5, whereby the lip, 63, will be moved into the path of the brake arm, 62, for stopping the 35 motor.

Briefly it may be stated that when the 35 train leaves the block both magnets will be de-energized, one releasing the governor mechanism of the motor and the other tending to re-engage the governor mechanism, but delayed in such action by the disk, 97, 40 until the motor has rotated sufficiently to raise the gate.

I provide a signal lamp, 99, fixed to the 45 gate near the center thereof and which is preferably constructed similarly to an automobile headlight and provided with a red lens so as to warn motorists at night when the gate is being actuated. A switch is provided, mounted on the post, 41, and contained within a suitable casing, 100. This 50 switch may be of any suitable construction so as to be actuated by the movement of the lever, 42, and for the purpose of illustration I have shown in Fig. 3 a pivoted switch 55 arm, 101, actuated by the link, 102, which is connected to the lever, 42, and adapted to close the circuit across the contacts, 103, and to energize the lamp, 99, through the medium of the wires, 104, and the battery, 105.

My gate is comparatively simple in 60 construction and may be made almost entirely of wood. The driving motor need not be of very large proportions and is protected from the elements and from damage by animals or human being. In the actual use 65 of my invention it will be necessary that a

service operator be provided to wind the motors and keep them in operative condition, as well as to charge the storage batteries.

It may be stated here that dry cells might readily be used for the magnetic controls, 70 and that in place of a lamp a warning device similar to those in popular use on highways at difficult curves and comprising, namely, a refractive and reflecting prismatic lens, might be employed. This would do 75 away with the necessity of the storage battery for lighting the lamp.

The service operator is to be provided with a suitable vehicle such as a hand car or motor-driven car to travel on the rails, 80 and each operator will be enabled thus to attend to a large number of crossing signals. It will be his duty to wind them every twenty-four hours. The motors may be of such size as to store power which will last forty-eight hours, so that if by any chance the 85 motors should be neglected for a day they would continue to operate.

It will be seen that the apparatus is especially adapted for use over long stretches of 90 railway where there is no available source of power and where storage batteries must be used. The expense of upkeep of storage batteries for actuating an electric motor would be prohibitive, but the current required by my apparatus is exceedingly small. 95

The operator is to be provided with mechanism for charging the batteries, which may be carried on the vehicle.

It is thought that the advantages of providing an automatic gate, actuated by the approach and recession of a train, are obvious. The ordinary automobile alarms now provided are ineffective for the reason that the sound of an automobile engine will exclude 100 the sound of a bell from the ears of the motorist. In order to eliminate the tendency of the motorist to try and beat the train to the crossing an actual barrier must be interposed in his path. 105

Some changes may be made in the construction and arrangement of the parts of my invention without departing from the real spirit and purpose of my invention, and it is my intention to cover by my claims 110 any modified forms of structure or use of mechanical equivalents which may be reasonably included within their scope.

I claim as my invention:

1. In an automatic crossing gate, a balanced gate pivoted for movement in a vertical plane, a pair of rails insulated from the remaining rails in a railway track, a relatively small spring motor having a 120 driven shaft, a crank arm thereon, operative means connecting the crank arm to the gate so as to move it from open to closed position and from closed to open position by rotation of the arm through periods of 180° respectively, means for locking the 125 gate in either position, a pair of rails 130

- motor against movement when the gate is in open position, means actuated by the establishing of a circuit across the rails for releasing the locking means, second means for again locking the motor when the arm has rotated through 180°, and second means for releasing the motor, said second releasing means being actuated by the breaking of the circuit across the rails.
- 10 2. In an automatic crossing gate, a balanced gate pivoted for movement in a vertical plane, a pair of rails insulated from the remaining rails in a railway track, a relatively small spring motor having a driven shaft, a crank arm thereon, operative means connecting the crank arm to the gate so as to move it from open to closed position and from closed to open position, means for locking the motor against movement when the gate is in open position, means actuated by the establishing of a circuit across the rails for releasing the locking means, second means for again locking the motor when the arm has rotated through 180°, and second means for releasing the motor, said second releasing means being actuated by the breaking of the circuit across the rails.
- 15 3. In an automatic crossing gate, a balanced gate pivoted for movement in a vertical plane, a pair of rails insulated from the remaining rails in a railway track, a relatively small spring motor adapted by successive periods of movement in the same direction to move the gate from open to closed position and from closed to open position respectively, means for locking the motor against movement when the gate is in open position, means actuated by the establishing of a circuit across the rails for releasing the locking means, second means for again locking the motor when the gate has reached closed position, and second means for releasing the motor, said second releasing means being actuated by the breaking of the circuit across the rails.
- 20 4. In an automatic crossing gate, a balanced gate pivoted for movement in a vertical plane, a pair of rails insulated from the remaining rails in a railway track, a relatively small spring motor adapted by successive periods of movement in the same direction to move the gate from open to closed position and from closed to open position respectively, means for locking the motor against movement when the gate is in open position, means actuated by the establishing of a circuit across the rails for releasing the locking means, second means for again locking the motor when the gate has reached closed position, and second means for releasing the motor, said second releasing means being actuated by the breaking of the circuit across the rails.
- 25 5. In an automatic crossing gate, a balanced gate pivoted for movement in a vertical plane, a pair of rails insulated from the remaining rails in a railway track, a relatively small spring motor adapted by successive periods of movement in the same direction to move the gate from open to closed position and from closed to open position respectively, means for locking the motor against movement when the gate is in open position, means actuated by the establishing of a circuit across the rails for releasing the locking means, second means for again locking the motor when the gate has reached closed position, and second means for releasing the motor, said second releasing means being actuated by the breaking of the circuit across the rails.
- 30 6. A control mechanism for a spring driven motor adapted by successive periods of rotation in the same direction to move a railway crossing safety device from inoperative position to operative position and from operative to inoperative position respectively, including a pair of rails insulated from the remaining rails in a railway track, means for locking the motor against movement when the gate is in open position, means actuated by the establishing of a circuit across the rails for releasing the locking means, second means for again locking the motor when the gate has reached closed position, and second means for releasing the motor, said second releasing means being actuated by the breaking of the circuit across the rails.
- 35 7. In an automatic crossing gate, a balanced gate pivoted for movement in a vertical plane from open to closed position obstructing a street and from closed to open position, a relatively small spring motor for moving the gate in either direction, a pair of rails insulated from the remaining rails in a railway track, and electrically controlled means for controlling the rotation of the motor, said latter means being controlled by the establishing and breaking of a circuit across the rails.
- 40 8. In an automatic crossing gate, a balanced gate pivoted for movement in a vertical plane from open to closed positions and from closed to open positions, a relatively small spring motor adapted, by successive periods of movement in the same direction, to actuate the gate from open to closed and from closed to open positions, respectively, a pair of rails insulated from the remaining rails in a railway track, and electrically controlled means actuated by the making and breaking, respectively, of a circuit across the rails for successively allowing the starting of the motor.
- 45 9. In an automatic crossing gate, a balanced gate pivoted for movement in a vertical plane from open to closed positions and from closed to open positions, a relatively

small spring motor adapted, by successive periods of movement in the same direction, to actuate the gate from open to closed and from closed to open positions, respectively, a pair of rails insulated from the remaining rails in a railway track, electrically controlled means actuated by the making and breaking of a circuit across the rails for allowing the motor to begin said periods of movement, and automatic means for stopping the motor at the end of said periods of movement.

10. In an automatic crossing gate, a balanced gate pivoted for movement in a vertical plane, a pair of rails insulated from the remaining rails in a railway track, a relatively small spring motor adapted by successive periods of movement in the same direction to move the gate from open to closed position and from closed to open position, respectively, means for locking the motor against movement when the gate is in open position, means actuated by the establishing of a circuit across the rails for releasing the locking means, second means for again locking the motor when the gate has reached closed position, second means for releasing the motor, said second releasing means being actuated by the breaking of the circuit across the rails, and auxiliary means for causing the second releasing means to operate while the circuit remains established across the rails.

11. In an automatic crossing gate, a gate, a motor for actuating the gate including a spring-driven power shaft, a governor shaft geared to the power shaft in ratio ascending from the power to the governor shaft, means carried by the power shaft to transmit movement to the gate, a braking arm having a frictional connection with the governor shaft, and mounted for rotation therewith, and an electrically controlled member movable into the rotational path of the braking arm.

12. In an automatic crossing gate, a pair of rails insulated from the remaining rails of a railway track, a gate, a motor for actuating the gate including a spring driven power shaft, means carried by the power shaft to transmit movement to the gate, a governor shaft geared to the power shaft in ratio ascending from the power to the governor shaft, a pair of braking arms having frictional connections with the governor shaft and mounted for rotation therewith, a first trigger member extending normally into the path of rotation of one of said

braking arms, means actuated by the closing of a circuit across the rails for moving said trigger to inoperative position, means for retaining said trigger in inoperative position until the power shaft has rotated through a predetermined arc, a second trigger member movable into the path of rotation of the other braking arm, and means for moving said second trigger to operative position when the power shaft has rotated a predetermined arc.

13. In an automatic crossing gate, a pair of rails insulated from the remaining rails of a railway track, a gate, a motor for moving the gate including a spring driven power shaft, a governor shaft geared thereto in ratio ascending from the power to the governor shaft, a pair of arms mounted for rotation with said governor shaft, a first trigger member disposed normally in the path of one of said arms, means actuated by the establishing of a circuit across the rails to release said trigger, a second trigger member movable into engagement with the other arm, means for moving said second trigger into operative position when the power shaft has rotated through a predetermined arc, said last means being rendered inactive by the breaking of the circuit across the rails.

14. In an automatic crossing gate, a pair of rails insulated from the remaining rails of a railway track, a gate, a motor for moving the gate including a spring driven power shaft, a governor shaft geared thereto in ratio ascending from the power to the governor shaft, a pair of arms mounted for rotation with said governor shaft, a first trigger member disposed normally in the path of one of said arms, means actuated by the establishing of a circuit across the rails to release said trigger, a second trigger member movable into engagement with the other arm, means for moving said second trigger into operative position when the power shaft has rotated through a predetermined arc, said last means being rendered inactive by the breaking of the circuit across the rails, and means for retaining the first trigger in inoperative position until the power shaft has rotated through a predetermined arc greater than the aforementioned arc.

Signed at Remsen, in the county of Plymouth and State of Iowa, this 20th day of May, 1924.

WILLIAM HARDER.
